UNITED STATES PATENT OFFICE.

EMIL LESKE, JR., OF NEW YORK, N. Y.

ATTACHMENT FOR MITER BOXES.

Application filed April 27, 1925. Serial No. 26,219.

To all whom it may concern:

Be it known that I, EMIL LESKE, Jr., a citizen of the United States of America, and a resident of the city of New York, borough of Bronx, in the county of Bronx and State of New York, have invented a new and Improved Attachment for Miter Boxes, of which the following is a full, clear, and exact description.

This invention relates to miter boxes, and has for its object the provision of a device for supporting a saw in order to furnish a plurality of varied cuts and in which the saw is not only guided in the cutting movement but supported at the same time.

Another object of the invention is the provision of a device for supporting and guiding the well known cross-cut saw for cutting miters in such a manner that a cut is produced, which is as effective for all purposes as the cuts provided by the usual miter saws.

A further object of the invention is the provision of a device for supporting a saw for cutting miters and in which the depth of the cut may be regulated as desired.

With the above recited and other objects in view, the invention resides in the novel construction set forth in the following specification, particularly pointed out in the appended claim and illustrated in the accompanying drawings, it being understood that the right is reserved to embodiments other than those actually illustrated herein, to the full extent indicated by the general meaning of the terms in which the claim is expressed.

In the drawings—

Figure 1 is a plan view of a miter device constructed according to the principle of my invention;

Figure 2 is a side view in elevation of the same;

Figure 3 is a transverse vertical section of the miter box;

Figure 4 is a vertical section taken along the line 4—4 of Figure 2;

Figure 5 is a transverse vertical section taken along the line 5—5 of Figure 2; and

Figure 6 is a horizontal section through a guide of the miter box taken along the line 6—6 of Figure 2.

Referring more particularly to the drawings, 10 designates a base having a guide 11 secured at its lower end, as shown at 12, to one side edge of the base 10 and intermediate the ends of said base member and disposed

within a passage formed in a wall 10^a which rises from one edge of the base. This guide, as shown more particularly in Figure 6, is formed of two parallel curved vertical bars 13 which are spaced apart and connected at their upper ends by means of a plate 14. A second guide 15 is formed of two spaced vertical bars 16 connected at their upper ends by means of a top plate 14. The inner faces of each of the guides 11 and 15 are grooved at 17 along the arc of a circle in order to receive a cylindrical post 18 which forms a support for a horizontal bar 19, which in turn supports the saw 20. The lower ends of the vertical bars 16 of the guide 15 are rigidly secured to a block 21 which has an undercut groove 22 to receive a T-shaped track 23 secured to the side edge of the base member 10, which is opposite the wall 10^a, so that the block 21 is 75 100 105 110 115 120 125 130 135 140 145 150 155 160 165 170 175 180 185 190 195 200 205 210 215 220 225 230 235 240 245 250 255 260 265 270 alignment with the inner projecting end 33 of the supporting member 34.

An adjustable bar 44 is provided with a slot 45 to receive a threaded bolt 46 carrying a thumb nut 47. The opposite end of the bolt 46 is provided with a socket 48 adapted to receive the end of the supporting bar 19. Depending from the bar 44 is a U-shaped bracket 50 provided with a set screw 51 threaded into an opening in one arm of the clamp 50 which is adapted to engage one face of the handle 52 of the saw when the handle is received within the U-shaped clamp 50 for locking the inner end 15 of the saw in position on the bar 44.

It will be noted that the bar 19 is disposed within passages 52 in the sliding posts 18. The lower ends of these posts are slotted, as shown at 53, to receive the saw 20 and aid 20 in guiding the saw during its cutting operation. In each of the guides 11 and 15 is located a plate 54 having upstanding stops 55 which are provided with inner flat faces and outer curved faces, with the outer curved 25 faces riding within the curved portion 17 of the guides 11 and 15. The plate 54 is provided with arms 56, and one of the arms is provided with a perforation into which is threaded a set screw 57 adapted to engage 30 a bar 16 of the respective guides 11 and 15 for locking the plate in position and likewise predeterminedly positioning the stops 55 for engagement with the lower end of the posts 18 and thereby limiting the downward 35 movement of the posts during the cutting action of the saw, which also limits the vertical movement of the saw, and will at all times maintain the cutting edge of the saw out of engagement with the base member 10.

40 In applying the saw, it is only necessary to insert the small end 58 of the saw through the longitudinal passages 59 formed between the vertical bars of the guides 11 and also through the slots 53 formed in the posts 18. 45 The end 58 of the blade of the saw is received in the lower end of the supporting member 34 and locked against movement by means of the set screw 36. The handle 52 of the saw is then inserted within the U-shaped 50 clamp 50 and set screw 51 is tightened, whereby the saw is rigidly supported from the bar 19. The thumb piece 25 is then manipulated and the plunger removed from the perforation, when the block 21 is shifted 55 longitudinally of the base member on its track 22 until the proper angle is located by means of the notch 31. The plunger is then released, when the same will fall into a perforation 26 adjacent the designation of the 60 angle on the scale 30.

If it be desired to complete the entire cut through the wood, the plates 54 are lowered to their extreme position at the bottom of the guides 11 and 15 so that the upper ends of the stops 55 will engage the lower ends of

the posts 18 and thus permit the saw to complete the cut without engaging the base member 10. Whatever depth of cut may be desired may be had by properly positioning the plates 54 within the guides 11 and 15, 70 the depth of the uncut portion of the work being indicated by a scale 60 over which the plates pass in vertical adjustment.

The top plates 14 are provided with passages 61 to receive the U-shaped clips 62 75 secured to the upper ends of the guide posts 18. The clips are bent to form notches 63 which are engaged by complementary formed lugs 64 projecting into the passages 61. When it is desired to place the saw 20 80 in position so that the work may be removed or replaced, it is only necessary to raise the saw together with the supporting posts 18 until the clips are forced through the passages 61 when the saw will be suspended 85 above the work and base 10.

In making miter cuts for producing sections of a hollow post or pillar and where it requires three or more sections to complete a segment of said post or pillar, the block 90 21 is shifted until the inner edge of said block alines with one of the marks adjacent one of the numerals 4, 6 or 8 and the plunger 24 will at this time engage one of the perforations in the scale 23. Thus when four 95 sections are required, the block is moved to the point on the scale 23 where the inner edge of said block alines with the indicating notch adjacent the numeral 4 when the plunger 24 will drop into the perforation below the designation of 90° and the blocks will then be cut at an angle of 90°. When it is desired to cut an end of the block to form a six-sided figure the inner edge of the block 21 is moved until it engages the indicating 100 line adjacent the numeral 6 and the plunger 24 will fall into the perforation below the designation 60°. When the saw is operated the ends of the blocks will be cut off at an angle of 60° so that a six-sided pillar or post 105 will be formed by such cuts. It also must be borne in mind that the other end of the work may be cut at the desired number of degrees by shifting the block 21 until the plunger 24 engages the perforation adjacent 110 the numeral 6, 8 or 4 so that the other end of the sliding block 21 will aline with the indicating marks adjacent the respective numerals 6 or 8 and which are located to the 115 left of the indicating mark 4.

The device permits of the use of an ordinary cross cut saw for effecting miter cuts instead of the usual miter saw and the guides will also maintain the saw in a vertical position so that a true miter is formed.

Having thus described my invention, I claim:

A device of the character described comprising a base, a hollow guide rigidly mounted on one side edge of the base and provided 130

with vertical slots, a track at the other side edge of the base, a movable hollow guide provided with slots slidably mounted on the track, a post vertically movable in each 5 guide, said post being provided with slots, a supporting bar mounted in the slots, clamping means at the opposite ends of the supporting bar for securing the opposite ends of a saw to the supporting bar, one of 10 said clamping means being adjustable longitudinally of the supporting bar, said bar being slidable through the slots in the post and the saw being slidable through the slots in the guide means for locking the movable 15 guide in one of a plurality of different positions at opposite sides of the transverse

center of the base for producing varying angular cuts with the saw, plates slidably mounted in the hollow posts and carrying stops adapted to engage the lower end of 20 said posts for limiting the downward movement of the posts and likewise the downward movement of the saw, and means on the plate engageable with the hollow guide for locking the plates in various vertical positions, lugs at the upper end of each guide and a resilient clip on the slidable posts 25 adapted to engage the lugs for retaining the posts and likewise the saw in an inoperative position.

EMIL LESKE, JR.
